UNITED STATES PATENT OFFICE.

SAMUEL B. SCHENCK, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed February 5, 1927. Serial No. 166,138.

This invention relates to control apparatus and more particularly to control apparatus for gas-electric power systems.

The object of the invention, generally stated, is the provision of an actuating handle for control apparatus that shall be simple and efficient in operation and readily and economically manufactured.

A more specific object of the invention is to provide for the actuation of predetermined groups of control members of a gas-electric power system and the locking of other control members against operation when a selected group has been operated.

A further object of the invention is to assure the actuation of all the control members to their neutral positions before the actuating handle can be removed.

Other objects of the invention will, in part, be obvious, and will, in part, appear hereinafter.

The invention, accordingly, is disclosed in the embodiment thereof shown in the accompanying drawing and comprises the features of construction, combination of elements, and arrangement of parts which will be exemplified in the construction hereinafter set forth and the scope of the application of which will be indicated in the claims.

For a general understanding of the nature and objects of the invention, reference should be had to the following detailed description taken in conjunction with the accompanying drawing, in which;

Fig. 1 is a sectional view of an actuating handle for control apparatus constructed in accordance with this invention and showing it associated with switching members which are illustrated diagrammatically,

Fig. 2 is a bottom plan view of one of the switch-actuating members provided in conjunction with the actuating handle,

Fig. 3 is a top plan view of a second switch-actuating member provided on the actuating handle,

Fig. 4 is a top plan view of an interlock provided on the actuating handle, and

Fig. 5 is a diagram of a control system with which this invention may be used.

Referring now to the drawings, a shaft 10 may be utilized for operating the throttle of a gas engine or some other prime mover to control the fuel supply. As shown, the shaft 10 is disposed near a panel 11, which is provided with a plurality of openings 12 and 13

for receiving a metal plug 14, as illustrated in Fig. 4. The panel may be of any suitable type in which a plurality of contact members are disposed adjacent each opening to engage the plug 14, so that the latter may be utilized for establishing selected circuits.

In the illustrated embodiment of the invention, two switches 15 and 16, which are illustrated diagrammatically, are disposed for operation by the actuating handle to be described hereinafter. As will be observed, both of the switches are of the spring-pressed type. However, it will be readily understood that any suitable toggle switch may be utilized, and the selection of a switch will depend on the circuits to be controlled.

In order to provide for the actuation of the shaft 10, a handle 17 is provided. As shown, the handle comprises an actuating member or grip 18 provided with an opening 19 shaped to fit over the squared end 20 of the shaft 10.

In multiple-unit gas-electric trains, it often becomes necessary to transfer the operator from one end of the train to the other, or from one car to another, and, in order to provide for the transfer of the actuating handle, the opening 19 is made large enough to permit it to be readily mounted on, or removed from, the shaft 10. Ordinarily, in such systems, it is necessary to mount the handle 17 on the shaft in a predetermined neutral position.

As will be observed by referring to Fig. 1, the switch 15 is adapted to control two circuits. As illustrated, the contact plate 21 of the switch 15 is normally held in engagement with contact fingers 22 and 23 by a spring 24. However, the contact plate 21 may be actuated into engagement with contact fingers 25 and 26, thereby to establish one circuit and interrupt another in a manner that will be set forth hereinafter.

In order to provide for the operation of the switch 15, a switch-actuating member 27 is slidably mounted in the hollow grip or actuating member 18. According to the illustration, the switch-actuating member 27 includes a head 28 and a stem 29, which is provided with a threaded end 30. The head 28 is provided with a slot 31 through which the squared end 20 of the shaft 10 may extend when the actuating handle is mounted thereon. Therefore, the switch-actuating member 27 may be moved longitudinally, relative to

the handle 18, for the purpose of actuating the switch 15.

In this construction, the member 27 is biased to the right by a spring 32, which is disposed in a chamber 33 provided in the grip or hand piece of the handle 17. As illustrated, the spring is interposed between the wall defining the inner end of the chamber 33 and a cap 34 mounted on the threaded end 10 30 of the stem 29 of the switch-actuating member.

Accordingly, the switch-actuated member is normally retained out of engagement with the switch 15. An upwardly extending semi-circular flange 35 is provided on the head 28 of the switch-actuating member 27 and disposed in alignment with a shank 36 provided on the contact plate 21 of the switch 15. Therefore, when the switch-actuating member 27 is manually operated to thrust it to the left, as viewed in Fig. 1, the shank 36 of the switch 15 is engaged, and the switch member is projected into engagement with the contact fingers 25 and 26.

25 In order to retain the switch plate 21 of the switch 15 in engagement with the contact fingers 25 and 26, a lock is provided.

The locking means for the switch-actuating member 27 and the switch 15 is best shown 20 in Fig. 2. As illustrated, a bracket 37, adapted for mounting on any suitable support, is disposed adjacent the head of the switch-actuating member 27. A roller 38 is mounted on the end of the bracket and located in 35 alignment with a semi-circular depending flange 39 provided on the lower face of the head 28 of the switch-actuating member 27. The flange 39 is notched at 40 to permit it to be projected over the roller 38 when the handle is set in its neutral position.

A second switch-actuating member 41 constitutes, in this particular case, as illustrated 45 in Fig. 3, a cam that may be either formed on the underside of the actuating handle 17 or attached thereto in any suitable manner. As will be observed, the switch-actuating cam 41 is provided with a depression 42, which is disposed to receive a shank 43 provided for actuating the bridging member 44 of the switch 50 16. Normally, the bridging member 44 of the switch 16 is retained in its open position by a spring 45, and may be projected into engagement with contact fingers 46 and 47 when the switch-actuating member 41 is operated 55 by the movement of the handle 17.

In order to prevent the insertion of the plug 14 into, or the withdrawal of it from, one of the openings in the panel 11, after the switch-actuating member 27 has been operated to establish predetermined circuits, and the handle 17 has been actuated from its neutral position, two upwardly extending flanges 48 and 49, which form an interlocking device, are provided on the actuating member 60 65 18. These flange members are so disposed

that, when the handle is set in its neutral position to close the throttle through the actuation of the shaft 10, access may be had to the openings 12 and 13.

In operation, when it is desired to actuate 70 the switch member 15 to bridge the contact fingers 25 and 26, the switch-actuating member 27 is moved to the left, and the roller 38 passes through the notch 40. If the actuating handle is now moved to rotate the shaft 75 10, a section of the flange 39 passes behind or to the left of the roller 38 and locks the switch-actuating member 27, so as to retain the switch member 21 in engagement with the contact fingers 25 and 26.

80 It will be readily understood that, when the actuating handle 17 has been moved out of its neutral position, one of the flanges 48 or 49 is moved in front of the openings 12 and 13, thereby preventing access to the panel to remove or insert the plug 14 after the shaft 10 has been operated to open the throttle. The operation of the handle from its neutral position also operates the cam 41 to close the switch 16 against the action of the spring 45.

85 If the handle 17 is actuated from its neutral position before the switch-actuating member 27 is projected to the left, one portion of the flange 39 is moved in front or to the right of the roller 38, thereby locking the switch-actuating member against operation. From the foregoing, it will be readily understood that the switch-actuating member 27 90 may be operated only when the handle 17 is in its neutral position.

95 In order that the construction and operation of the actuating handle may be clearly understood, a simple control circuit for a gas-electric power system with which it may be utilized, will now be described. In the 100 control system illustrated diagrammatically in Fig. 5, a generator 50, that may be driven by a gas engine, is connected to supply energy to motors 51 and 52. A field winding 53 of the generator may be supplied from 105 any suitable source of electrical energy, such as a battery 54.

110 Assume now that it is desired to operate the motors 51 and 52 in parallel relation and in the forward direction. A switch 55 is actuated to connect the battery across the generator field winding 53 and also to connect the battery 54 for supplying the control circuits. While the actuating handle 17 is still in the neutral position, the metal plug 14 is inserted 115 in the opening 13 in the panel 11, and the switch-actuating member 27 is manually operated to the left to actuate the switch 15 and project the plate 21 into engagement with the contact fingers 25 and 26.

120 125 130 If now, the actuating handle 17 is moved in the forward direction, the switch 16 is closed by cam 41, as described above, and a circuit extends from the battery 54 through switch 55, conductor 56, switch 16, conductor 57,

plug 14 mounted in the opening 13, contact fingers 58 and 59, bridged by contact segment 60 of the reverser drum controller 61, conductors 62 and 63, contact fingers 25 and 26, 5 bridged by the contact plate 21 of the switch 15, conductor 64, and through the parallel-connected actuating coils of the switches 65 and 66, to the battery through conductor 67.

The switches 65 and 66 are thus closed, 10 and the motors 51 and 52 are connected in parallel relation across the generator 50. The motor circuits may be traced from the positive terminal of the generator 50 through conductor 68, the parallel-connected motors 15 51 and 52, and conductor 69 back to the generator.

From the foregoing description, it will be evident that the switch 15 cannot be actuated to interrupt the established motor connections, and the plug 14 cannot be withdrawn 20 until the actuating handle 17 has been returned to its neutral position.

Further, assume that the actuating handle 17 is operated to rotate the shaft 10 before 25 the switch-actuating member 27 is operated. The switch 15 is, therefore, retained in engagement with the contact fingers 22 and 23, and, when the handle 17 is moved from its neutral position, the switch-actuating member 30 is locked against operation. The movement of the handle 17 effects the actuation of the switch 16, and a circuit is established from the energized conductor 63 through contact fingers 22 and 23, bridged by the contact plate 21 of the switch 15, conductor 70, the actuating coil of the switch 71, and conductor 67, back to the battery. The motors are now 35 connected in series relation and current flows from the generator 50 through conductor 68, motor 51, conductor 72, switch 71, motor 40 52, and conductor 69 to the generator.

From the foregoing description, it will be seen that a simply constructed and efficient 45 operating handle for actuating the control members of a gas-electric control system has been provided. The members of the handle are so disposed that, when predetermined circuits are established, they cannot be interrupted until the handle is actuated to its neutral 50 position, thereby reducing the speed of the engine and the voltage of the generator to a safe amount for the interruption of certain circuits and the establishment of other circuits.

55 Since certain changes may be made in the above construction and different embodiments of the invention may be made without departing from the scope thereof, it is intended that all matter contained in the above 60 description or shown in the accompanying drawing shall be interpreted as illustrative and not in a limiting sense.

I claim as my invention:

65 1. In control apparatus, in combination, an actuating handle, switch-actuating means

movably mounted on the handle, means for locking the switch-actuating means, said locking means being adapted to permit free movement of the switch-actuating means when the handle is in a predetermined position, and a switch-actuating member disposed for operation by the movement of the handle. 70

2. In control apparatus, in combination, an actuating handle, switch-actuating means carried by the handle and disposed for manual operation, and means for locking the switch-actuating means when the handle is moved from a predetermined position. 75

3. In control apparatus, in combination, an actuating handle, switch-actuating means carried by the handle and disposed for manual operation, locking means for the switch-actuating means, said locking means being adapted to permit operation of the switch-actuating means when the handle is in a predetermined neutral position, and an interlock carried by the handle and disposed to function when the handle is moved from said neutral position. 80

4. In control apparatus provided with a 85 shaft, in combination, a handle adapted to be mounted on the shaft in a predetermined neutral position, a switch-actuating member movably mounted on the handle, and means for locking the switch-actuating member when the handle is moved from its neutral position to 90 actuate the shaft. 95

5. In control apparatus provided with a shaft, in combination, a handle adapted to be mounted on the shaft in a predetermined neutral position, a switch-actuating member 100 movably mounted on the handle, means for locking the switch-actuating member when the handle is moved from its neutral position to actuate the shaft, an auxiliary switching member, and interlocking means carried by the handle for preventing the operation of the auxiliary switching member when the handle is moved from its neutral position. 105

6. In control apparatus provided with a 110 shaft, in combination, an actuating handle adapted to be mounted on the shaft in a predetermined neutral position, a manually operable switch-actuating member movably mounted on the handle, means for locking the switch-actuating member when the handle is moved from the neutral position to actuate the shaft, and a second switch actuating member disposed to function when the handle is actuated. 115

7. In control apparatus provided with a shaft and a plurality of switches, in combination, an actuating handle adapted to be mounted on the shaft in a neutral position, a manually operable switch-actuating member 125 carried by the handle and disposed for operation independently of the handle, means for locking the switch-actuating member when the handle is moved from the neutral position, a second switch-actuating member dis- 130

posed for operation by the actuation of the handle, an independent switching member and interlocking means carried by the handle whereby the independent switching means may be locked against operation when the handle is actuated from its neutral position.

8. In control apparatus provided with a shaft, in combination, an actuating handle 10 adapted to be mounted on the shaft in a neutral position, a manually operable switch-actuating member carried by the handle and disposed for operation independently of the handle, a locking member for locking the 15 switch-actuating member against movement relative to the handle after the handle has been actuated from its neutral position, an auxiliary switching member and flange members carried by the handle and disposed to 20 move in front of said auxiliary switching member to lock it against operation when said switching actuating member has been locked in a predetermined position.

9. In control apparatus provided with a shaft, in combination, an actuating handle 25 adapted to be mounted on the shaft in a predetermined neutral position, a manually operable switch-actuating member slidably mounted on the handle, resilient means for 30 retaining the switch-actuating member in a predetermined position, and a locking member disposed to engage said switch-actuating member when it has been manually moved from said predetermined position and the 35 handle has been actuated from its neutral position.

10. In control apparatus provided with a shaft, in combination, an actuating handle

adapted to be mounted on the shaft in a predetermined neutral position, a slidably 40 mounted switch-actuating member carried by the handle, resilient means for biasing the switch-actuating member to a predetermined position, and a locking member for retaining the switch-actuating member in a position 45 to which it may be actuated against the action of said resilient means, said switch-actuating member being provided with a notched depending flange for engaging the locking member, said notched flange being 50 adapted to permit the switch actuating member to be actuated freely when the handle is in a predetermined position and to cooperate with the locking member to prevent the operation of the switch-actuating member when 55 the handle has been moved from its neutral position.

11. In control apparatus provided with a shaft and a plurality of switches, in combination, an actuating handle adapted to be 60 mounted on the shaft in a predetermined neutral position, a slidably mounted switch-actuating member carried by the shaft, resilient means for biasing the switch-actuating member to a predetermined position, means 65 for locking the switch-actuating member in different positions when the handle has been actuated from its neutral position, and means for preventing the operation of one of said switches when the switch-actuating member 70 has been locked in a predetermined position.

In testimony whereof, I have hereunto subscribed my name this 2nd day of February, 1927.

SAMUEL B. SCHENCK.
